United States Patent Office.

EDWIN ALLEN, OF NORWICH, CONNECTICUT, ASSIGNOR TO ALLEN MANUFACTURING COMPANY, OF SAME PLACE.

Letters Patent No. 70,063, dated October 22, 1867.

IMPROVEMENT IN MECHANICAL MOVEMENT.

The Schedule referred to in these Letters Patent and making part of the same.

TO ALL WHOM IT MAY CONCERN:

Be it known that I, EDWIN ALLEN, of Norwich, in the county of New London, and State of Connecticut, have invented a new and useful Improvement in Mechanical Movements; and I declare that the following is a sufficiently exact description of the same to enable one skilled in the art to which my invention appertains to make use of it, reference being had to the accompanying drawing, which is made a part of this specification, and which represents a face view of a pair of gear-wheels illustrating my invention.

My invention consists of a pair of gear-wheels, of irregular form, adapted to transmit an equal relative rotation to two press-cylinders, one of which has any desired number of straight surfaces or planes, and the other convex surfaces corresponding in number and superficial length with the straight surfaces of the first cylinder, as will be hereinafter explained. The invention is applicable to presses for stamping, cutting, printing, or other purposes where it may be found desirable to have straight surfaces on one cylinder, acted on by convex surfaces on the other, with uniform pressure, without friction or stoppage.

In the drawings, A represents a compound gear-wheel, whose "pitch" or working line is made up of three chords *a a a*, of sixty degrees, united by three sections, each composed of a curve, *b*, (concentric with the wheel,) and two straight lines *c c*. D represents a compound gear-wheel, whose pitch or working line consists of three arcs *d d d*, of such length and convexity as to mesh accurately with the straight surfaces or chords *a a a* of the wheel A, united by three sections, each consisting of two curves *e e*, of the same radius as the curves *d*, and a curve, *f*, concentric with the wheel D and of such radius that the distance from *g* to *h* on the wheel D (measured around the pitch line) will be equal to the distance from *i* to *j* on the wheel A.

In applying my invention, the wheel A will be keyed upon the shaft of the die-cylinder, or of the platen-cylinder of a printing-press, or any other press-cylinder to which it may be adapted and applied, so as to bring the planes *a a a* in exact coincidence with the flat surfaces upon which the platens, dies, or other devices are mounted. In like manner the wheel B is to be keyed upon the shaft of the pressure-cylinder, with its regular curves *d d d* corresponding in position with the curved surfaces which bear upon the face of the dies or type on the first cylinder. The curves *d d d* being made of equal length with the planes *a a a*, so as to adapt one to pass over the other without friction, it is manifest that the chords *a* will occupy a larger proportion of the periphery of the wheel than the arcs *d*, (their superficial length being equal,) and hence that while the surfaces *a* and *d*, and the corresponding plane and curved surfaces of the press-cylinders pass in contact at uniform speed, the mean distance of the pitch line of the arcs *d* from the centre of the wheel D should be less than that of the pitch line of the planes *a* from the centre of the wheel A. By this means I adapt the wheels and their cylinders respectively to rotate with uniform speed. The intermediate sections *c b c* and *e f e*, constructed as described, insure the coincidence of the pressing surfaces of the respective cylinders. If the distance between the centres of the wheels A and D be ten inches, the radius of the curves *d* and *e* should be two and eleven-twentieth inches, and the curve *f* concentric with the wheel, as before explained.

Having thus described my invention, what I claim as new, and desire to secure by Letters Patent, is—

The gear-wheel A, constructed with one or more chords *a*, whose ends are connected by irregular sections *c b c*, in combination with the gear-wheel D, composed of a corresponding number of arcs, *d*, with irregular connecting sections *e f e*, all as herein represented and described.

To the above specification of my improvement in mechanical movements I have signed my hand this 23d day of August, 1867.
